UNITED STATES PATENT OFFICE.

THEODOR V. BAUER, OF BERLIN, GERMANY.

COKE-OVEN.

1,026,894.

Specification of Letters Patent. Patented May 21, 1912.

Application filed May 4, 1908. Serial No. 430,699.

To all whom it may concern:

Be it known that I, THEODOR VON BAUER, engineer, citizen of Germany, subject of the King of Prussia and Emperor of Germany, residing at Berlin, W. 15, in the Kingdom of Prussia and Empire of Germany, have invented certain new and useful Improvements in Coke-Ovens, of which the following is a full, clear, and exact description.

This invention relates to improvements in the manufacture of coke with or without the simultaneous recovery of the by-products.

All of the processes heretofore known for the production of coke, and of coke ovens heretofore employed are subject to the drawback that on the one hand the heating power of the waste gases is only imperfectly utilized, while on the other hand the heating of the oven is not carried out to the best advantage.

In the systems heretofore usually employed, the flues or combustion chambers which are the nearest to the place of entry of the gases usually consume the greater part thereof, with the result that too little gas is supplied to the combustion chambers which are situated at a greater distance, which arrangement has naturally resulted in the unequal heating of the several chambers.

The purpose of the present invention is to devise a method of uniformly heating the coke chambers by means of the waste gases in such manner that these gases are caused to flow in equal volumes over the whole of the coke battery as distinct from being supplied thereto in the form of a single current or flow. These separate and independent currents are supplied from above the retorts at which points they commingle with counter-currents of air that are supplied from under the retorts, which air currents are in their passage to the commingling point, preheated to a degree that will more readily and effectively facilitate combustion. The arrangement for supplying the waste gases to the combustion chambers is such that the various currents may be united in groups of different volumes, and means are also provided to deflect the currents of these volumes in different directions whereby the distribution thereof may be manually controlled. And a further means is devised whereby the pressure of gas within the sev-

eral divisions is kept uniform in each. This method of supplying waste gases from above may be used in connection with ovens having vertical chambers as well as with those having horizontal chambers. The supply pipes for feeding the waste gases to the combustion chambers may be disposed to either side of the coke oven and deliver centrally thereof, or they may be arranged centrally of the coke oven and distributed to the sides.

In the accompanying drawings,—Figure 1 is a vertical sectional view of a series of ovens taken through the combustion chambers and gas supplying passages. Fig. 2 is a transverse sectional view of Fig. 1, taken on the line N—M.

Referring to the drawings, wherein like letters of reference designate corresponding parts in the figures, the letters R, R indicate the pipes or mains for conducting the waste gases to be distributed to the combustion chambers. These pipes are provided with downwardly extending branches r from which lead outlets or nozzles b, c, d, e, which nozzles b, c, and d in turn communicate with passageways b', c' and d' that distribute the gaseous fuel to the several combustion chambers. These gas conducting ways are disposed inwardly and downwardly and at their terminals communicate with a common chamber a, and from said chamber the gas is delivered to the combustion chamber m, by way of communicating ducts a'. The inclined passage-ways are slightly different on the right and left of Fig. 1, but in both types they are inclined downwardly and inwardly. For equalizing the pressure of gas throughout all parts of the common chamber a there is a by-pass p in the central dividing wall. And for manually regulating the direction of flow of the gases from the several supply passage-ways b', c' and d' there are two baffle members s that are adapted to be moved along the common chamber a, and by this means serve to deflect the incoming flow of gases and direct the same either toward the central wall P or to the farther sides thereof all according to which combustion chambers need regulation.

The retorts S and the manner of supplying the material thereto are of that type usually employed on coke ovens of this general character, and since they form no part of this invention need not be described here.

The air for supporting combustion of the

gas within the chambers *m* is supplied thereto in this manner. Communicating with the under passages or arch ways *L* are inlet ducts *g* through which the air passes into a common chamber *h* whence it enters through ducts *h'* into a second common passage-way *h''* (see Fig. 2), and from here it passes by ducts *i* to a third chamber *i'*, and thence upwardly to the channels *k* disposed centrally of the walls *k'*. In passing through the tortuous passage-way just described the air is gradually heated until when passing upwardly through the channels *k* it is brought to the maximum temperature at which period it is delivered through the outlets *n* located near the top of the combustion chambers, and at which points it meets or commingles with the gas entering through the ducts *a'* from the chambers *a*. Combustion being effected at this the uppermost point of the combustion chamber is by reason of the disposition of the inlet passages caused to burn downwardly which fact is considered of much significance in coke ovens of this type. The products of combustion pass through the openings *l'* at the bottom of the chambers and into the by-ways *m'*, and thence by way of the passage *x* out through the common channel *K*.

While I have shown and described a particular arrangement for effecting the object in view, *i. e.*, the arrangement of counter-currents of combustible elements and supports therefor, and the downwardly burning of these elements, I do not wish to confine myself to this particular construction, but reserve the right to make such changes therein as will fall within the scope of the appended claim.

What is claimed as new is,—

In combination with a series of retorts, of combustion chambers in the side walls thereof, a gas distributing chamber located above said combustion chambers and communicating therewith, a slideable baffle member in said gas distributing chamber for regulating the direction of flow of gas to the combustion chambers, a plurality of channels for supplying gas to said distributing chamber, and flues for conveying pre-heated air to the combustion chambers.

In witness whereof, I subscribe my signature, in presence of two witnesses.

THEODOR v. BAUER.
